TEXTILE SPOOL

Rawson Atwood, Garden City, N. Y.

Application April 14, 1948, Serial No. 20,902

13 Claims. (Cl. 242—118)

1

This invention relates to improvements in spools.

More particularly, the invention is concerned with providing a textile spool or bobbin of improved construction in which a flange is securely interlocked with a barrel end and which may be manufactured simply and economically from components which do not require riveting or similar methods of attachment and hence may be made of a variety of materials, such as non-ductile metal, synthetic resins and the like.

For a full understanding of the invention, a detailed description of a bobbin embodying the invention in a preferred form will now be given in connection with the accompanying drawing and the features forming the invention will then be specifically pointed out in the appended claims.

In the drawing:

Fig. 1 is a view in central longitudinal section as to the upper part thereof and in elevation as to the lower part thereof, of a bobbin embodying the invention in a preferred form;

Fig. 2 is an end elevation of the bobbin of Fig. 1;

Fig. 3 is a detail plan view of a snap ring employed for holding the parts together; and

Fig. 4 is a view similar to the upper part of Fig. 1, but showing the parts in exploded relation, so as to illustrate the method of assembling.

The invention is shown as applied to a bobbin in which the construction at both ends is the same. However, the invention is also applicable to single flanged spools or pirns and may be applied to one end of a double flanged spool where desired.

The bobbin comprises a barrel 1 (Fig. 1) and end flanges 2, these parts being held in assembled relation by means of a bearing plug 3, split ring keeper 4 and drive ring retainer 5 as more particularly described below. The barrel is formed with a shoulder 6 against which the flange 2 is seated. Beyond the shoulder 6 the barrel 1 and flange 2 have, respectively, outer and inner surfaces 7 and 8 of substantially equal diameter. Toward the middle of the cylindrical reduced section 7 of the barrel, the barrel is formed with a recess in the form of a peripheral groove 9 which receives a keeper in the form of a split ring 4. The flange is formed with a shoulder 10 above the cylindrical section 8 and with an enlarged aperture having a cylindrical wall 11 of larger diameter above this shoulder, the parts defining annular spaces which accommodate part of the ring 4 and also accommodate the drive ring 5. The inside diameter of the barrel is enlarged somewhat at the end, forming an internal shoulder 12 and the cylindrical bearing plug 13 is

2

driven into the barrel so as to seat against the shoulder 12, as shown. The bearing plug has a central bore 13 serving as a bearing for a spindle or similar element and may be formed with 5 driving connections for drive lugs or the like wherever desired.

The bobbin may be formed of any desired materials having the requisite mechanical strength and characteristics of rigidity and flexibility required by the functions thereof. Various plastic materials may be employed, but the invention is not limited thereto, it being obvious that the various parts can be constructed of wood, metal or other materials to suit particular conditions.

The barrel, flange and other parts may be formed to the shapes shown by turning operations or by molding operations as convenient. The split ring 4 is preferably formed so that, when relaxed, it will have the form shown in Figure 3 and 20 may be dropped over the end of the barrel, assuming the position indicated in Figure 4. The relaxed inner diameter is then larger than the barrel end, while the peripheral measurement inside the ring is substantially the same as the periphery at the bottom of groove 9. As shown in Figs. 3 and 4, the ring 4 has an inner portion 20 shaped to fit the recess or groove 9 of the barrel, which in this case is rectangular in cross section, and an outer portion 21 which is beveled for cooperation with a corresponding inner bevel 22 25 of the retainer or drive ring 5. Drive ring 5 is otherwise shaped to fit the open space between barrel 1 and flange 2, so that, when the spool is assembled, the drive ring 5 and split ring 4 substantially fill all the open space, providing a practically solid end construction. The inner length of the snap ring 4 is preferably substantially equal to the circumference of the barrel at the inside of the groove 9 so that when the snap ring is forced inwardly into this groove its 30 ends will be in contact or will fail to make contact by only a small clearance. With the parts in assembled position, the drive ring 5 may seat against the shoulder 10, as shown, or may have a slight clearance therefrom so as to permit driving the split ring 4 inwardly under desired pressure.

The bevel angle for the split ring 4 and drive ring 5 is preferably selected with reference to the function coefficients of the materials used and 35 with reference to the force required to drive the snap ring inwardly, so that the construction is self-locking. A driving fit of the drive ring 5 between the barrel end and the cylindrical surface 11 is also preferably provided so as to close up 40 gaps in the end of the spool and hold the parts 45 50 55

firmly together. The bearing plug 3 supports and reinforces the end of the barrel against inward pressure created by forcing in of the split ring 4 and the driving fit of the drive ring 5.

The assembly of the bobbin of the invention is simple and will be largely obvious from the foregoing description of the parts. As indicated in Figure 4, bearing plug 3 and flange 2 are slid into place axially of the barrel 1, and snap ring 4 is dropped in as indicated. Then drive ring 5 is dropped in and driven home, completing the construction. While not ordinarily necessary, any of the contacting surfaces may be coated with adhesive, for more securely joining the parts.

All the parts described have been shown as formed integrally from homogeneous material. This is not inherent in the invention, however, as any of the parts may be composed of two or more members suitably fastened or fitted together and such members may be of the same or different materials. While it is preferred that the snap ring 4, when in relaxed condition, have an inner opening large enough to permit it to be dropped over the barrel end, this is not essential to the invention in its broader aspect, as a snap ring of smaller relaxed inner diameter may be used and the ring may be expanded in passing it over the end of the barrel.

The fit of the parts will normally be tight enough to prevent relative turning movement between the plug 3 and barrel 1 and between the barrel 1 and flange 2. Where required, however, longitudinal ribbing and grooving for preventing relative rotation may be provided. Such expedients being well known in the art and forming no part of the present invention, they are not shown herein.

What is claimed is:

1. A spool comprising, in combination, a barrel having a circumferential groove adjacent its end, a split ring fitting within the groove and protruding outwardly therefrom to form a shoulder, a flange having an inner aperture fitting around the barrel inwardly of the groove, a shoulder on the flange engaging under the shoulder formed by the split ring and an enlarged central aperture beyond the same, and a retainer fitted into the enlarged aperture of the flange for holding the split ring within the groove and keeping the flange on the barrel.

2. A spool according to claim 1, in which the split ring has a beveled outer rim and the retainer engages against the beveled outer rim for forcing the split ring into the groove.

3. A spool according to claim 2, in which the retainer is formed with an inner rim of corresponding bevel to the split ring and the retainer and split ring substantially fill the barrel groove and enlarged aperture of the flange.

4. A spool according to claim 1, in which the split ring is a ring with a single split, has a relaxed inner diameter as great as the barrel for slipping thereover and an inner periphery substantially equal to the circumference at the base of the groove.

5. A spool according to claim 4, in which the split ring has a beveled outer rim and the retainer engages against the beveled outer rim for forcing the split ring into the groove.

6. A spool according to claim 5, in which the retainer is formed with a beveled rim of corresponding bevel to the split ring and the retainer and split ring substantially fill the barrel groove and enlarged aperture of the flange.

7. A spool comprising, in combination, a barrel having an end of reduced diameter forming a shoulder for receiving a flange and a circumferential groove in the reduced end, a flange seated on the barrel shoulder and fitting around the reduced barrel end between the shoulder and groove, the flange having a shoulder registered with the inner wall of the groove and a central aperture of larger diameter than the reduced barrel end beyond the shoulder, a split ring fitting in the groove and protruding therefrom to form a shoulder overlying the flange shoulder to hold the flange in seated position on the barrel shoulder, and a retainer fitted in the enlarged central aperture of the flange for holding the split ring in the groove.

8. A spool according to claim 7, in which the split ring has a beveled outer rim and the retainer engages against the beveled outer rim for forcing the split ring into the groove.

9. A spool according to claim 8, in which the retainer is formed with an inner rim of corresponding bevel to the split ring and the retainer and split ring substantially fill the barrel groove and enlarged aperture of the flange.

10. A spool according to claim 9, in which the split ring is a ring with a single split, has a relaxed inner diameter as great as the barrel for slipping thereover and an inner periphery substantially equal to the circumference at the base of the groove.

11. A spool according to claim 10, in which the split ring has a beveled outer rim and the retainer engages against the beveled outer rim for forcing the split ring into the groove.

12. In a spool and in combination, a barrel having an end of reduced diameter forming a shoulder for receiving a flange and a recess in the reduced end, a flange seated on the barrel shoulder and fitting around the reduced barrel end between the shoulder and recess, the flange having a shoulder registered with the inner wall of the recess and a central aperture of larger diameter than the reduced barrel end beyond the shoulder, a keeper fitting in the recess and protruding therefrom to form a shoulder overlying the flange shoulder to hold the flange in seated position on the barrel shoulder, and a retainer fitted in the enlarged central aperture of the flange for holding the keeper in the groove.

13. A spool according to claim 12, in which the keeper and retainer are formed with corresponding bevels whereby the retainer forces the keeper into the recess.
